DESIGN FOR RUBBER OVERSHOES.

Specification forming part of Design No. 5,066, dated July 4, 1871.

To all whom it may concern:

Be it known that I, AUGUSTUS O. BOURN, of the city of Providence, in the county of Providence and State of Rhode Island, have originated a new and artistic Design for the Ornamentation of Gaiter Overshoe; and I do hereby declare that the following specification, taken in connection with the drawing furnished and forming a part of the same, is a clear, true, and exact description thereof.

Figure 1 represents a gaiter overshoe manufactured under my design. Fig. 2 represents the same in top view.

It is made up of a cloth anklet, A, a rubber

foxing, B, about the quarter and heel, a vamp, C, provided with raised ribs D, extending across the vamp between the cloth, and a raised toe-foxing, E, provided with a curved outline on the vamp.

Having thus described my design, I claim as new—

The above-described design for the ornamentation of gaiter overshoe as shown.

A. O. BOURN.
